REPEATER FUSE SWITCH

Charles Adin Fox, St. Louis, Mo., assignor to
 James R. Kearney Corporation, St. Louis, Mo.,
 a corporation of Missouri

Application June 18, 1938, Serial No. 214,403

9 Claims. (Cl. 200—126)

This invention relates generally to electrical fuse switches of the repeater type and more specifically to a switch of the type disclosed in an application for United States Letters Patent filed 5 in my name on July 2, 1937, Serial No. 151,587, the predominant object of the present invention being to provide an improved repeater switch of the type disclosed in the application for patent identified above which includes means for slowing 10 the operation of the switch as the effective path of the electrical current is transferred from one set of parts of the switch to another set of parts thereof so as to insure at all voltages complete interruption of the path of the current through 15 one set of parts of the switch before a path of current through another set of parts of the switch is established.

The repeater switch disclosed in the application for patent mentioned above has been found 20 to function in a highly efficient manner, but in order to eliminate any and all possibilities of failure in operation it has been considered advisable to slow down the current transfer action of the switch slightly when the switch is used with 25 voltages of 15 kv. or over. With voltages of less than 15 kv. no such slowing down action is required, and in connection with the higher voltages such slowing down action ordinarily is not essential, but, as stated above, in order to eliminate 30 any chance that the transfer action of the switch may be too rapid under some circumstances with higher voltages the switch is provided with means for slowing down the transfer action of the switch as hereinafter described.

In the operation of the switch when constructed as disclosed in my previously filed application for patent, the passage of current through the switch is transferred from one path to another in approximately a cycle and a half, and in 40 accordance with the arrangement disclosed in the present application such transfer is accomplished in from fifty to sixty cycles. By so slowing down the transfer action of the switch the likelihood that the secondary path of current 45 through the switch will be established before the primary path is completely interrupted is entirely eliminated.

Fig. 1 is a side elevation of the improved switch, parts thereof being shown in perspective 50 because of their angular disposition.

Fig. 2 is an enlarged, fragmentary vertical section illustrating the mechanism for slowing down the transfer action of the switch.

Fig. 3 is a front elevation of the switch illustrated in Fig. 1, here also parts of the switch be-

ing shown in perspective because of their angular disposition.

Fig. 4 is an enlarged, fragmentary section taken on line 4—4 of Fig. 1.

Fig. 5 is a fragmentary side elevation illustrating parts of the transfer mechanism and the slowing down mechanism associated therewith as these parts appear when transfer of the passage of current through the switch from one path to another has been accomplished.

In the drawings, wherein are shown for the purpose of illustration, merely, one embodiment of the invention A designates the improved switch generally. The switch A includes a suitable insulator B to which is attached a bracket C that 15 serves as means for securing the switch A to a cross arm or other support.

Secured to the insulator B adjacent to the upper end thereof is the upper terminal 1 of the improved switch, said upper terminal including a 20 block 1a which is provided with an arcuate face that contacts with the curved surface of the insulator, and a rigid arm 1b that extends upwardly from said block. The arm 1b of the upper terminal has associated therewith a suitable connector 2 for electrically connecting an electrical conductor (not shown) to the upper terminal.

Associated with the upper terminal 1 is an upper contact 3 which preferably, though not necessarily, is formed of heavy wire possessing resiliency. The upper contact 3 includes a portion 3a which embraces the insulator, this embracing portion being disposed in an annular groove formed in the insulator. Also the upper 35 contact includes a pair of slightly convergent portions which extend forwardly from the insulator embracing portion, and at points adjacent to the opposite sides of the block of the upper terminal, eyes 4 are formed in the forwardly extended portions of the upper contact. Extended 40 through the eyes 4 and through opposed washer elements 5 is a bolt 6 which serves to draw the forwardly extended portions of the upper contact toward each other whereby the insulator 45 embracing portion is caused to grip the insulator tightly and the upper terminal is securely attached to the insulator B.

Adjacent to the forward end of the upper contact 3 a sleeve 7 is provided which embraces the forwardly extended portions of said upper contact 50 so as to prevent undue spreading of said forwardly extended portions. Also at the extreme outer end of the upper contact the forwardly extended portions thereof are bent rearwardly upon 55

themselves as indicated at 8 and the rear end portions of said rearwardly bent portions are flared outwardly. As will be presently made plain herein the rearwardly bent forward portions 8 of the upper contact provide gripping portions which receive portions of fuse links associated with the switch, and the flared portions serve to guide the portions of the fuse links into said gripping portions. In order to prevent the rearwardly bent portions 8 from moving outwardly to an unnecessary degree and thereby destroying the gripping action of the gripping portions of the upper contact a cap 10 is frictionally applied to the outer end of the upper contact, in embracing relation with respect thereto.

The improved switch A includes a pair of lower contacts, one thereof, which is designated by the reference character 11, being attached to the insulator B at a point adjacent to the lower end 20 thereof, and the other lower contact, which is designated by the reference character 12, being attached to the insulator at a point a slight distance above the point of attachment of said lower contact 11. The means for attaching the lower contact 12 to the insulator B includes an arcuate member 13 having an arcuate face which is arranged in contact with the curved face of the insulator. The member 13 is secured to the insulator by a curved rod 14 which embraces the insulator in one of the annular depression of said insulator, the opposite end portions of said curved rod being extended through openings formed through portions of the member 13 and said opposite end portions of said rod being screw-threaded adjacent to their ends to receive nuts 15 which may be drawn up to cause the curved rod and the member 13 to tightly engage the insulator. The member 13 constitutes the lower terminal of the switch, being provided with an outwardly projected extension 16 which has associated therewith a suitable connector 17 through the instrumentality of which an electrical conductor (not shown) may be electrically connected to said extension.

The contact 12 preferably is formed from a single length of heavy wire and it includes a horizontal loop 18 at its inner end, said contact 12 being secured to an extension 19 of the arcuate member by a bolt 19' whose shank extends 50 through the loop 18 of the contact and into an opening formed in said extension 19. From the loop 18 divergent portions 22 (Fig. 3) of the contact 12 extend forwardly and continuations of these divergent portions 22 are bent helically to 55 provide the contact with opposed spring portions 23 which give to the contact the required resiliency.

The portions 22 of the contact 12 enter the centers of the helically wound spring portions and 60 leading from the lower, outer portions of said spring portions is a pair of parallel contact portions 24 which terminate in convergent portions 25. From the forward ends of the convergent portions 25 parallel and relatively closely positioned 65 contact portions 26 are extended forwardly and at the forward end of the contact these portions 26 are bent rearwardly upon themselves as indicated at 27 to provide gripping portions, similar to the gripping portions of the upper contact 3, 70 which are adapted to engage portions of fuse links as will presently appear herein. Extended from the rearwardly bent portions 27 are outwardly flared portions 28 which serve to guide fuse links into the gripping portions. In order 75 to prevent undue spreading of the contact por-

tions 26 sleeves 29 are provided which embrace said portions, and in like manner to prevent excessive outward movement of the rearwardly bent portions 27 a cap 30 is applied to the outer end portion of the contact in embracing relation with 5 respect thereto.

The means for attaching the lower contact 11 to the insulator B comprises a member 31 which is provided with an arcuate face that contacts with the curved outer face of the lower portion 10 of the insulator B, said member being secured to the insulator by a bolt 33 which extends through an opening formed through said member and through an aperture formed through the 15 wall of the hollow insulator B.

The lower contact 11 is constructed and arranged just as is the lower contact 12 which has already been described in detail herein; that is to say said lower contact 11 includes a loop at its inner end, opposed helically wound spring 20 portions 38, spaced apart portions 38' which extend forwardly from the lower portions of the spring portions, convergent portions 39, adjacent- 25 ly positioned, forwardly extended portions 40, and rearwardly bent portions 41 at the outer end of 25 the contact which provide gripping portions having flared guides 42 associated therewith. Likewise the contact 11 has sleeves 43 associated with the portions 40 thereof and a cap 44 applied to the outer end of the contact, the sleeves and cap being intended to prevent undue spreading of parts 30 of the contact. The contact 11 is secured to the insulator by the bolt 33 heretofore referred to, the shank of said bolt passing through the up- 35 standing loop of the contact.

The member 31 that supports the lower contact 11 includes an extension which supports a transfer contact 48. This transfer contact is made preferably of a single length of heavy wire 40 possessed of resiliency and it includes an up- 45 standing loop from the lower end of which forwardly extended portions 50 are projected. At the forward ends of the portions 50 of the transfer contact 48 the length of wire from which the transfer contact is formed is bent upwardly 50 as shown at 51 in Fig. 3. The length of wire is then bent downwardly in parallelism with the portions 51 as shown at 52, and the remaining portions of the length of wire are bent upwardly in spaced relation with respect to the portions 50 as indicated at 53, the upper end portions of 55 said portions 53 being flared outwardly to provide inclined guides 54. The transfer contact is provided with a sleeve 55 which prevents undue spreading of the portions 50 thereof, and said transfer contact is secured to the member 31 by a bolt 56 in the same general manner that the lower contacts 11 and 12 are secured to the members 31 and 13.

In its fully fused condition the improved switch 60 includes a pair of fuse links 60 and 61 of like construction and arrangement. Each of these fuse links comprises a pair of flexible cables 62 which are spaced apart at their inner ends to 65 provide a gap, and a fusible element (not shown) which is electrically and mechanically connected to the inner end portions of said cables is disposed in said gap. The fusible element and the adjacent inner portions of the flexible cables 62 70 of each fuse link are enclosed within a tube 64 which preferably is formed of horn fiber or other material that is characterized by the ability to give off a gas in the presence of the heat of an electric arc which tends to extinguish said electric arc. The tube 64 of each fuse link is inter- 75

posed between and is supported by a collar 64a and a coil spring 64b that are supported by the cables 62. At the outer ends of the cables 62 of each fuse link loops 66 are formed and fixed to the flexible conductors in close proximity to the loops are stop buttons 67.

When the improved switch is fully fused the lower flexible cable of the fuse link 60 is drawn into one of the gripping portions at the outer end portion of the lower contact 11, while the lower flexible cable of the fuse link 61 is drawn into one of the gripping portions at the outer end portion of the lower contact 12. Also when the lower flexible cables have been drawn into gripping portions of the lower contacts 11 and 12 as stated above, the lower stop buttons 67 contact with the under sides of said lower contacts. Furthermore during the fully fused position of the improved switch the upper flexible cables of the fuse links 60 and 61 are drawn into the gripping portions of the upper contact 3, the upper flexible cable of the fuse link 60 being drawn into the gripping portion at one side of the upper contact, and the upper flexible cable of the fuse link 61 being drawn into the gripping portion at the opposite side of the upper contact.

In assembling the fuse links 60 and 61 in place in the switch said fuse links are applied to the switch one at a time. Ordinarily the switch is located in an elevated position and when this is so the operator passes the transverse finger of a fuse stick through the loop at the upper end of the fuse link so that the link is suspended from said finger. He then raises the suspended fuse link and pulls it outwardly so as to draw the portion of the lower flexible cable immediately above the button 67 deep into the gripping portion of the lower contact with which the fuse link is being assembled. The operator then raises the fuse link to the proper elevation and then pulls the upper portion of said fuse link outwardly so as to draw a portion of the upper flexible cable deep in one of the gripping portions of the upper contact. When the operator raises the fuse link with its lower end attached to a lower contact he winds the helical spring portions of the lower contact with the result that said lower contact is placed under considerable tension which tends to draw the outer end of the lower contact downwardly. When the first fuse link has been applied to the switch as described the second fuse link is assembled with the switch in like manner whereupon the switch is ready for use.

When the improved switch is fully fused and in use electrical energy passes from the terminal 1 through the upper contact to and through the fuse link 61 to the lower contact 12, and from said lower contact through the lower terminal 13 to the conductor connected thereto. It is to be noted that when the switch is fully fused no current passes through the fuse link 60 due to the fact that the lower contact 11 is out of electrical connection with respect to the lower terminal 13. Now, if with the switch fully fused a fault occurs in the circuit, the fusible element of the fuse link 61 will part and thereby release the tensioned lower contact 12 which will move downwardly in response to action of the helical spring portions 23. This will quickly separate the severed ends of the ruptured fusible element so as to quickly extinguish the electric arc produced by severance of the fusible element, such extinguishment of the electric arc being aided

by the gas produced within the tube 64 when the horn fiber thereof is subjected to the heat of the electric arc.

When the outer portion of the lower contact 12 is moved downwardly as described the forwardly extended portions 24 of said lower contact 12 move into the spaces between the upright portions 52 and 53 of the transfer contact 48. The course of the current then is from the upper terminal through the upper contact 3, to and through the fuse link 60 to the lower contact 11. From the lower contact the current passes through member 31 with which the lower contact 11 is associated to the transfer contact 48 and from said transfer contact to and through the lower contact 12, which at this time contacts with the transfer contact 48, to the lower terminal 13 and the conductor connected thereto.

The switch thus far described in detail herein is constructed and operates in accordance with the switch disclosed in my previously filed application for patent identified above. The invention of the present application relates to means for slowing down the speed of movement of the lower contact 12 when the fuse link 61 associated therewith is ruptured and the outwardly extended portion of said contact moves downwardly to make contact with the transfer contact 48, and this means will now be described.

The extension 19 of the member 13 which serves as the lower terminal of the switch includes an outwardly and upwardly inclined housing portion 70 which preferably, though not necessarily, is of the shape illustrated to the best advantage in Fig. 2. The housing portion 70 is closed at its opposite sides by plates 71 which are secured in place by means of tie rods 72. Supported for rotation by the opposed side plates 71 of the housing portion 70 is a shaft 73 on which is fixedly mounted a gear wheel 74 of relatively large diameter. The gear wheel 74 meshes with a pinion 75 (Fig. 4) which is mounted for rotation on a shaft 76 that is non-rotatably supported by the side plates 71 of the housing portion 70, and said pinion is provided with a hub or sleeve portion 75' on which a gear wheel 77 is fixedly mounted. The gear wheel 77 in turn meshes with a pinion 78 which is loosely mounted on the shaft 73 for rotary movement with respect thereto, and this pinion is provided with a hub or sleeve portion 78' on which a gear wheel 79 is fixedly mounted. The gear wheel 79 meshes with a pinion 80 which is supported by the fixed shaft for rotation with respect thereto, and said pinion 80 is provided with a sleeve 81 to which is splined or otherwise received, a fly wheel 82. At its opposite end the fly wheel 82 is provided with a bearing 83 which is supported by the fixed shaft 76 for rotation with respect thereto, said bearing contacting with the adjacent side plate 60 of the housing portion 70 so as to prevent movement of the fly wheel and its associated parts laterally of the housing.

From the foregoing arrangement it is obvious that when the shaft 73 is rotated rotary motion will be imparted by the gear wheel 74 fixed to said shaft 73 to the pinion 75 and because of the relative sizes of the gear wheel 74 and the pinion 75 the speed of rotation of the pinion will be much greater than the speed of rotation of the gear wheel. Also rotation of the pinion 75 will be transmitted by the gear wheel 77 fixed to said pinion, to the pinion 78 mounted for rotation relative to the shaft 73 and here also the speed of rotation of the pinion 78 will be greatly in-

creased because of the relative sizes of the gear wheel 11 and the pinion 18. Additionally, rotation of the pinion 18 will be transferred by the gear wheel 19 fixed to said pinion to the pinion 20 with a consequent increase in speed of rotation of the pinion 20 due to the relative sizes of said gear wheel and pinion, and because the fly wheel 22 is fixed to the pinion 20 it will rotate there-with at a rate of speed greatly in excess of the speed of rotation of the shaft 13.

Fixed to the shaft 13 adjacent to its opposite ends is a pair of arms 24 which extend from the shaft 13 parallel with respect to each other and with respect to the side plates of the housing portion 10 to points slightly beyond the curved outer end wall of said housing portion. At these points the arms extend inwardly toward each other as shown to the best advantage in Fig. 3, and at the inner ends of said inwardly extended arm portions, outwardly extended ears 24' are provided. Pivotally attached to the ears 24' of the arms 24 by means of a pivot 25 is a pair of links 26. At their opposite ends the links 26 are pivoted by means of pivots 27 to upstanding ears 28 which are secured to a plate 29, said plate 29 having apertures formed therethrough through which the parallel portions 24 of the contact 12 extend and said plate being secured to said contact portions 24 by solder or otherwise.

When in the operation of the improved switch disclosed herein the fuse link 31 is ruptured, the outwardly extended portion of the lower contact 12 is freed from restraint and as a result of the tension stored up in the spiral spring portions 23 said extended portion of said contact immediately starts to move downwardly toward the transfer contact 48. However, because the additional burden of rotating the fly wheel 22 and the speed reducing gearing associated therewith is applied to the downwardly moving contact 12 its speed of movement is reduced to a substantial degree with the result that sufficient time is available under any and all conditions to interrupt the passage of current through the path of which the ruptured fuse link forms a part before the new path of current is established. An important feature of the invention is that energy is stored up in the rapidly rotating fly wheel as the contact 12 moves toward the transfer contact 48 and this energy in the form of centrifugal force drives the contact portions 24 of the contact 12 deep into tight contact with portions of the transfer contact to make good electrical contact between these parts.

I claim:

1. A fuse switch including a tensioned, inherently resilient, contact element, contact means into contact with which said tensioned contact element is movable in response to energy stored up therein, said contact means including spaced portions between and in contact with which a portion of said contact element is movable to make electrical contact between said contact element and said contact means, and means connected to said contact element and including a rotating member and speed-reducing gearing associated therewith for converting the energy of said contact element into kinetic energy which delays movement of the contact element into contact with the contact means and serves when contact is made between the contact element and the contact means to force said portion of the contact element between and into close contact with the spaced portions of said contact means.
2. A repeater fuse switch comprising an insulating support, a terminal, substantially rigid

contact means supported by said insulating support in electrical connection with said terminal, a primary and a secondary contact supported by said insulating support in spaced relation with respect to said contact means and with respect to each other, a second terminal arranged in electrical connection with said primary contact, a pair of fuse links mechanically and electrically connecting said primary contact and said secondary contact to said contact means, a transfer contact arranged in electrical connection with said secondary contact and into electrical contact with which said primary contact is adapted to move when the fuse link associated therewith is ruptured, said primary contact being formed of resilient material and the fuse link associated therewith serving to hold said primary contact in a slightly bowed condition when said primary contact is connected to said contact means whereby the outer end portion of said primary contact receives initial rapid movement as it straightens from its bowed condition on rupture of the associated fuse link, and rotary means engaged with said primary contact for regulating the speed of movement of said primary contact as it moves toward said transfer contact and after said initial rapid movement of the outer end portion thereof.

3. A repeater fuse switch comprising an insulating support, a terminal, substantially rigid contact means supported by said insulating support in electrical connection with said terminal, a primary and a secondary contact supported by said insulating support in spaced relation with respect to said contact means and with respect to each other, a second terminal arranged in electrical connection with said primary contact, a pair of fuse links mechanically and electrically connecting said primary contact and said secondary contact to said contact means, a transfer contact arranged in electrical connection with said secondary contact and into electrical contact with which said primary contact is adapted to move when the fuse link associated therewith is ruptured, said primary contact and said secondary contact being formed of resilient material and the fuse link associated therewith serving to hold said primary contact in a slightly bowed condition when said primary contact is connected to said contact means whereby the outer end portion of said primary contact receives initial rapid movement as it straightens from its bowed condition on rupture of the associated fuse link, and rotary means engaged with said primary contact for regulating the speed of movement of said primary contact as it moves toward said transfer contact and after said initial rapid movement of the outer end portion thereof.

4. A repeater fuse switch comprising a single insulating support, a terminal, substantially rigid contact means supported by said insulating support in electrical connection with said terminal, a primary and a secondary contact supported by said insulating support in spaced relation with respect to said contact means and with respect to each other, a second terminal arranged in electrical connection with said primary contact, a pair of fuse links mechanically and electrically connecting said primary contact and said secondary contact to said contact means, a transfer contact arranged in electrical connection with said secondary contact and into electrical contact with which said primary contact is adapted to move when the fuse link associated therewith is ruptured, said primary contact being

- formed of resilient material and the fuse link associated therewith serving to hold said primary contact in a slightly bowed condition when said primary contact is connected to said contact means whereby the outer end portion of said primary contact receives initial rapid movement as it straightens from its bowed condition or rupture of the associated fuse link, and rotary means engaged with said primary contact for regulating the speed of movement of said primary contact as it moves toward said transfer contact and after said initial rapid movement of the outer end portion thereof.
5. A repeater fuse switch comprising an insulating support, a terminal, substantially rigid contact means supported by said insulating support in electrical connection with said terminal, a primary and a secondary contact supported by said insulating support in spaced relation with respect to said contact means and with respect to each other, a second terminal arranged in electrical connection with said primary contact, a pair of fuse links mechanically and electrically connecting said primary contact and said secondary contact to said contact means, a transfer contact arranged in electrical connection with said secondary contact and into electrical contact with which said primary contact is adapted to move when the fuse link associated therewith is ruptured, said primary contact being formed of resilient material and the fuse link associated therewith serving to hold said primary contact in a slightly bowed condition when said primary contact is connected to said contact means whereby the outer end portion of said primary contact receives initial rapid movement as it straightens from its bowed condition on rupture of the associated fuse link, rotary means engaged with said primary contact for regulating the speed of movement of said primary contact as it moves toward said transfer contact and after said initial rapid movement of the outer end portion thereof, and connecting means for operatively connecting said primary contact and said rotary means.
6. A repeater fuse switch comprising an insulating support, a terminal, substantially rigid contact means supported by said insulating support in electrical connection with said terminal, a primary and a secondary contact supported by said insulating support in spaced relation with respect to said contact means and with respect to each other, a second terminal arranged in electrical connection with said primary contact, a pair of fuse links mechanically and electrically connecting said primary contact and said secondary contact to said contact means, a transfer contact arranged in electrical connection with said secondary contact and into electrical contact with which said primary contact is adapted to move when the fuse link associated therewith is ruptured, said primary contact being formed of resilient material and the fuse link associated therewith serving to hold said primary contact in a slightly bowed condition when said primary contact is connected to said contact means whereby the outer end portion of said primary contact receives initial rapid movement as it straightens from its bowed condition on rupture of the associated fuse link, rotary means engaged with said primary contact for regulating the speed of movement of said primary contact as it moves toward said transfer contact and after said initial rapid movement of the outer end portion thereof, and connecting means for

operatively connecting said primary contact and said rotary means, said connecting means comprising a link pivotally attached at its opposite ends to said primary contact and said rotary means respectively.

7. A repeater fuse switch comprising a single insulating support, a terminal, substantially rigid contact means supported by said insulating support in electrical connection with said terminal, a primary and a secondary contact supported by said insulating support in spaced relation with respect to said contact means and with respect to each other, a second terminal arranged in electrical connection with said primary contact, a pair of fuse links mechanically and electrically connecting said primary contact and said secondary contact to said contact means, a transfer contact arranged in electrical connection with said secondary contact and into electrical contact with which said primary contact is adapted to move when the fuse link associated therewith is ruptured, said primary contact being formed of resilient material and the fuse link associated therewith serving to hold said primary contact in a slightly bowed condition when said primary contact is connected to said contact means whereby the outer end portion of said primary contact receives initial rapid movement as it straightens from its bowed condition on rupture of the associated fuse link, rotary means engaged with said primary contact for regulating the speed of movement of said primary contact as it moves toward said transfer contact and after said initial rapid movement of the outer end portion thereof, and connecting means for operatively connecting said primary contact and said rotary means, said rotary means being supported by said single insulating support, and said connecting means comprising a link pivotally attached at its opposite ends to said primary contact and said rotary means respectively.

8. A repeater fuse switch comprising a single insulating support, a terminal, substantially rigid contact means supported by said insulating support in electrical connection with said terminal, a primary and a secondary contact supported by said insulating support in spaced relation with respect to said contact means and with respect to each other, a second terminal arranged in electrical connection with said primary contact, a pair of fuse links mechanically and electrically connecting said primary contact and said secondary contact to said contact means, a transfer contact arranged in electrical connection with said secondary contact and into electrical contact with which said primary contact is adapted to move when the fuse link associated therewith is ruptured, said primary contact being formed of resilient material and the fuse link associated therewith serving to hold said primary contact in a slightly bowed condition when said primary contact is connected to said contact means whereby the outer end portion of said primary contact receives initial rapid movement as it straightens from its bowed condition on rupture of the associated fuse link, rotary means engaged with said primary contact for regulating the speed of movement of said primary contact as it moves toward said transfer contact and after said initial rapid movement of the outer end portion thereof, and connecting means for operatively connecting said primary contact and said rotary means, said rotary means being supported by said single insulating support and be-

ing a part of said second terminal, and said connecting means comprising a link pivotally attached at its opposite ends to said primary contact and said rotary means respectively.

5 9. A repeater fuse switch comprising an insulating support, a terminal, contact means supported by said insulating support in electrical connection with said terminal, a primary contact and a secondary contact supported by said 10 insulating support in spaced relation with respect to said contact means and with respect to each other, a second terminal arranged in electrical connection with said primary contact, a pair of fuse links mechanically and electrically connecting said primary contact and said secondary contact to said contact means, a transfer contact for placing said primary contact in elec-

trical connection with said secondary contact when the fuse link associated with said primary contact is ruptured, said primary contact being formed of resilient material and the fuse link associated therewith serving to hold said primary 5 contact in a slightly bowed condition when said primary contact is connected to said contact means whereby the outer end portion of said primary contact receives initial rapid movement as it straightens from its bowed condition on rupture of the associated fuse link, and means 10 cooperating with said primary contact for regulating the speed of movement of said primary contact as it moves toward said transfer contact and after said initial rapid movement of the 15 outer end portion thereof.

CHARLES ADIN FOX.
